US0D1075342S

(12) **United States Design Patent** (10) **Patent No.:** **US D1,075,342 S**
(45) **Date of Patent:** **** May 20, 2025**

(54) **MODULAR FURNITURE ASSEMBLY WITH BASE AND MULTIPLE UPRIGHT MEMBERS**

(71) Applicant: **THE LOVESAC COMPANY**, Stamford, CT (US)

(72) Inventors: **Shawn D. Nelson**, Washington, UT (US); **David M. Underwood**, Hurricane, UT (US)

(73) Assignee: **The Lovesac Company**, Stamford, CT (US)

(**) Term: **15 Years**

(21) Appl. No.: **29/806,405**

(22) Filed: **Sep. 2, 2021**

Related U.S. Application Data

(63) Continuation of application No. 17/028,738, filed on Sep. 22, 2020, now Pat. No. 11,253,073, which is a continuation of application No. 16/189,859, filed on Nov. 13, 2018, now Pat. No. 10,806,261, which is a continuation of application No. 15/826,090, filed on Nov. 29, 2017, now Pat. No. 10,154,733, which is a continuation of application No. 15/058,656, filed on Mar. 2, 2016, now abandoned, which is a continuation-in-part of application No. 14/993,533, filed on Jan. 12, 2016, now Pat. No. 10,070,725, and a continuation-in-part of application No. 14/332,705, filed on Jul. 16, 2014, now Pat. No. 9,277,826, which is a continuation of application No. 13/164,721, filed on Jun. 20, 2011, now Pat. No. 8,783,778, said application No. 14/993,533 is a continuation-in-part of application No. 12/967,671, filed on Dec. 14, 2010, now Pat. No. 9,277,813, said application No. 13/164,721 is a continuation-in-part of application (Continued)

(57) **CLAIM**

The ornamental design for a modular furniture assembly with base and multiple upright members as shown and described.

DESCRIPTION

The sole FIGURE is a perspective view of a modular furniture assembly with base and multiple upright members. The broken lines depict portions of the article that form no part of the claimed design.

The stippling illustrated in the sole FIGURE depicts a contrast in material.

1 Claim, 1 Drawing Sheet

Related U.S. Application Data

No. 12/484,931, filed on Jun. 15, 2009, now Pat. No. 7,963,612, which is a continuation-in-part of application No. 11/449,074, filed on Jun. 8, 2006, now Pat. No. 7,547,073, which is a continuation-in-part of application No. 11/149,913, filed on Jun. 10, 2005, now Pat. No. 7,213,885.
